UNITED STATES PATENT OFFICE.

ADOLPH A. HANSON, OF DECORAH, IOWA.

FIRE PROTECTION FOR STORES.

SPECIFICATION forming part of Letters Patent No. 783,634, dated February 28, 1905.

Application filed July 19, 1904. Serial No. 217,188.

To all whom it may concern:

Be it known that I, ADOLPH A. HANSON, a citizen of the United States, residing at Decorah, in the county of Winneshiek and State of Iowa, have invented a certain new and useful Fire Protection for Stores, of which the following is a specification.

The objects of my invention are to provide an apparatus of simple, durable, and inexpensive construction that may be readily and quickly applied to a building for the purpose of automatically removing from the building show-cases containing valuable articles and protecting by fireproof curtains other articles that cannot be readily removed in case a fire started at any point throughout the entire building.

My invention consists in certain details in the construction, arrangement, and combination of the various parts of the device whereby the objects contemplated are attained, as hereinafter more fully set forth, pointed out in my claims, and illustrated in the accompanying drawings, in which—

Figure 1 shows a sectional view of a building provided with my improved apparatus. Fig. 2 shows an enlarged detail view illustrating means for supporting one of the fireproof curtains and for releasing it when a rope is pulled. Fig. 3 shows a detail view illustrating the means for automatically sounding an electric bell when a rope is pulled. Fig. 4 shows a detail perspective view of a show-case for containing valuable articles arranged to be bodily removed from a building when a rope is pulled. Fig. 5 shows a detail perspective view of a display-table, illustrating means for spreading a fireproof sheet over the table when a rope is pulled. Fig. 6 shows a detail perspective view illustrating the means for automatically unlocking and opening a door when a rope is pulled, and Fig. 7 shows an enlarged detail sectional view of the fuse-box and connected parts.

Referring to the accompanying drawings, I have used the reference-numeral 10 to indicate the building, 11 a window in the building, and 12 a pair of hinged doors, all of common construction. At a convenient point within the building—such, for instance, as the upper story—I place a metal fuse-box 13, hav-

ing a perforated front plate. Slidably supported in the top of the fuse-box is a metal tube 14, to which a rope 15 is attached. This rope 15 extends upwardly and then over a number of direction-pulleys 16. One end of the rope is attached to a sliding pin 17, which pin is held in place by a thin wooden strip 18, which may be easily broken. The other end of the rope is provided with a weight 19, which weight will descend as soon as the tube 14 is released from the fuse-box, and it will also break the wooden strip 18 and withdraw the pin 17. The said rope 15 is made of fire-proof material. Passed through the bottom of the fuse-box 13 is another tube, 20, slidably mounted in the fuse-box, and the tubes 20 and 14 are connected by means of the cords 21, which are made of material that will readily burn. Attached to the lower end of the tube 20 is a rope 22 made of a material that will easily burn. This rope passes over a number of direction-pulleys 23 and is arranged throughout those parts of the building where a fire is likely to occur. The opposite end of the rope is fixed to a stationary support at 24, and the rope 22 is stretched taut by the upward pull of the tube 14 on the tube 20. If a fire should occur in any part of the building adjacent to the rope 22, the said rope would be easily ignited and burned off, thus permitting the rope 19 to elevate the tubes 14 and 20.

I have provided an additional means for releasing the rope to which the weight 19 is attached as follows: In the fuse-box 13 I place a quantity of readily-ignitable substance 25, and communicating with the fuse-box is a pipe 26, leading to a part of the building where a fire is likely to occur and where it may not be desirable to run the rope 22. In the pipe 26 I have placed a readily-ignitable fuse 27, one end of which enters the fuse-box 13 and the other end projects to the other end of the pipe. Hence if this fuse is ignited the fuse will rapidly burn and ignite the material 25 in the fuse-box, so that the cords 21 will be burned off and the weight 19 be permitted to descend.

I have provided means for automatically removing a show-case from the building in the event that the weight 19 descends as fol-

lows: The numeral 28 indicates a frame for supporting a show-case 29, which frame is supported on the wheels 30 and is provided at its top with the hangers 21, in which the 5 rollers 32 are mounted. An elevated track 33 is located in the building and extends through the doorway, to which the doors 12 are applied, and projects to the point exterior to the building. At the end of the show-case 10 29 adjacent to the doors I have provided a handle 34. The said track 33 is arranged at such height from the floor that when the rollers 32 are on the track the rollers 30 will clear the floor. To provide a firm base for 15 the show-case, I place the blocks 35 on the floor under the rollers 30, thus elevating the rollers 32 above the track 33. The numeral 36 indicates a rope, attached to the end of the show-case farthest from the doorway. This 20 rope passes above the track 33 and under a direction-pulley 37, positioned above the doorway. The said rope also travels over a direction-pulley 38, mounted on a bracket 39, located on the exterior of the building. Sup- 25 ported on the bracket 38 is a pivoted shelf 40, upon which a weight 41 on the end of the rope 36 is placed. This shelf 40 is normally held in an elevated position by a prop 42, the lower end of which is supported by 30 the sliding pin 17. Hence when the sliding pin 1 is withdrawn the prop 42 drops and the shelf 40 swings downwardly. Immediately below the shelf 40 is a deflector 43, designed to receive the weight 41 to permit it to slowly descend 35 by gravity until it reaches the end of the deflector, whereupon it will quickly drop. In this way the pull upon the rope 36 at first is relatively slow and gradual, and after the weight has moved a short distance it may 40 quickly drop. Obviously when the weight 41 descends the show-case will first be moved toward the door until the rollers 30 pass beyond the blocks 35. Then the show-case will travel on the rollers 32 and track 33, and as the 45 doors 12 are open the show-case will be moved to the exterior of the building, and the first movement of the show-case will be relatively slow and will gradually increase as it moves toward the doorway.

50 I have provided means for automatically opening the doors 12 when the rope 36 is pulled upwardly as follows: Connected with each of the doors 12 is a contractile coil-spring 44, the other end of which is attached at 45 to the 55 point within the building, thus normally applying a yielding pressure in the direction tending to open the door. Fixed to the inner face of each door 12 is a bracket 46. A cross-piece 47 is provided, and on its ends are the 60 wedges 48, normally resting in the brackets 46, thus forming a lock for the doors. Attached to the cross-piece 47 is a rope 49, which rope is attached at 50 to the rope 36. Hence 65 when the said rope 36 is pulled the rope 49 is elevated, the doors unlocked, and then opened by the springs 44. I have also provided means for automatically spreading a fireproof sheet over tables and over such articles as cannot be easily removed from a building as follows: The numeral 51 indicates a table provided at 70 its sides with the tracks 52. Mounted upon said tracks are the brackets 53, provided with rollers 54, traveling on the said tracks. The said brackets 53 support a roller 55, upon which a fireproof sheet 56 is wound. One end 75 of the sheet is attached to the end of the table, and a rope 57 is attached to the brackets 53 and to the frame 28 of the show-case, so that when the show-case moves toward the doorway the rope 57 will unroll the fireproof sheet over the table 51. I have also provided means whereby stationary shelves in the building may be protected by a fireproof curtain as follows: The numeral 58 indicates a set of shelves, and supported near the top thereof 80 is a fireproof curtain 59, wound upon a roller 60. The numeral 61 indicates a rope passed around the central portion of the curtain in its rolled-up position, and said rope 61 is opened upon a pin 62, which is slidingly 85 mounted in a support 63, so that when the pin 62 is pulled the rope 61 will be released therefrom and the curtain will unroll by gravity to cover the shelf 58. The pin 62 is attached to a rope 64, which rope is connected 90 with the rope 15, before described. A rope 65 is also connected with the rope 15 and arranged to support a fireproof curtain 66 to cover the window 11 the same as the curtain 59 is supported.

95 I have provided means for automatically sounding an alarm in case the weight 19 descends as follows: The numeral 67 indicates an electric battery, and 68 an electric bell of ordinary construction. 69 indicates a wire 100 leading from the battery to the bell, and 70 a wire leading from a bell to a contact-point 71. The numeral 72 indicates a lever hinged at 73 and provided with a contact-point 74, connected by wires 75 with the battery. The 105 numeral 76 indicates a contractile coil-spring arranged to normally throw the lever 72 to position where the contact-point 74 will engage the contact-point 71. The numeral 77 indicates a block normally holding the lever 110 72, so that the contact-points are out of engagement. A rope 78 is attached to the block 77 and also to the rope 15, so that when the weight 19 drops the block 77 will be removed and the contact-points brought into engagement with each other and the electric bell operated by the battery.

115 In practical use it is obvious that my apparatus may be applied to buildings of any kind, and such articles as may be easily moved and 120 which contain valuable property may be arranged to be instantly carried out of the building in case a fire should originate at any point in the building. Furthermore, such articles as cannot easily be moved will be in- 125 130

stantly covered by fireproof curtain or sheets and also an electric alarm will be sounded that will continue to ring for an indefinite time.

Having thus described my invention, what I claim, and desire to secure by Letters Patent of the United States therefor, is—

1. In an apparatus of the class described, the combination with a building having a doorway, a door, a latch for the door, a show-case slidingly supported within the building, a rope attached to the show-case and to the door-latch and arranged when drawn to release the door-latch and to remove the show-case through the doorway and means actuated by fire within the building for drawing said rope.

2. In an apparatus of the class described, the combination of a building having a doorway, a door, a latch for the door, a show-case supported on rollers, a track above the show-case extended through the doorway, rollers at the top of the show-case resting on said track when the rollers that support the show-case are above the floor, blocks beneath the rollers that support the show-case to hold the show-case in position with its rollers above the track, a rope attached to the show-case and to the said latch and means actuated by a fire within the building for drawing said rope.

3. In an apparatus of the class described, the combination of a table, tracks on the side of the table, brackets slidingly mounted on said tracks, a roller supported by said brackets, a fireproof sheet wound upon the roller and having one end fixed to one end of the table, a rope connected with said brackets and means actuated by a fire within the building for drawing the roller toward the end of the table opposite from the point where the fireproof sheet is attached.

4. In an apparatus of the class described, the combination with a building, of a bracket supported on the exterior of the building, a shelf hinged to the bracket, a prop supporting the outer end of the shelf, a sliding pin supporting the prop, a weight resting on the shelf, a pulley above the weight, a rope passed over the pulley and attached to the weight and means actuated by a fire within the building for withdrawing the pin.

5. In an apparatus of the class described, the combination of a rope, pulleys for supporting the rope, a weight on one end of the rope, a sliding pin on the other end of the rope, a device connected with the rope normally supporting the weight, said device released automatically by fire within the building, a wooden strip normally holding the said pin in position, said strip arranged to be broken by the pull of the weight upon the rope when the device attached to the rope is released by fire and means actuated by the withdrawal of the said pin for protecting articles within the building.

6. In an apparatus of the class described, the combination with a building, of a bracket sup-

ported on the exterior of the building, a sliding pin in said bracket, a wooden strip holding said pin in position, a rope attached to the pin, means actuated by a fire within the building for breaking the strip and withdrawing the pin, a shelf hinged to the said bracket, a prop supporting said shelf and resting upon said pin, a deflector beneath the shelf, a weight resting on the shelf, a rope connected with the weight and means actuated by a downward movement of the weight for protecting articles within the building.

7. In an apparatus of the class described, the combination of a fireproof curtain having one end attached to an elevated support, a rod having the curtain wound thereon, a cord supporting the wound-up curtain, a sliding bolt supporting the cord, a rope connected with the sliding bolt and means for automatically pulling the rope to release the cord, said means actuated by a fire within the building.

8. In an apparatus of the class described, the combination of an electric circuit, an electric bell included in the circuit, a lever in one position establishing a circuit from the battery to the bell and in another position breaking the circuit, a spring normally holding the lever in position for establishing a circuit, a removable block normally holding the lever in position for breaking the circuit and a rope attached to the removable block and means automatically actuated by a fire within a building for pulling the rope.

9. In an apparatus of the class described, means for automatically pulling a rope upon the occurrence of a fire, said means comprising a box, inflammable material in the box, a fuse communicating with the inflammable material, an inflammable cord in the box, a rope connected with the inflammable cord, said rope released when the cord is burned and a weight attached to the rope.

10. In an apparatus of the class described, the combination of a building, a fuse-box within the building, a sliding tube in the top of the fuse-box, a non-inflammable rope connected with the sliding tube, a pulley above the fuse-box having said rope passed over it, a weight attached to the rope, a sliding tube in the bottom of the fuse-box, inflammable cords connecting said sliding tubes within the fuse-box, a readily-ignitable rope connected with the lower sliding tube, pulleys for supporting said rope, means for fixing the opposite end of the rope, a tube communicating with the fuse-box, a fuse in the tube and means actuated by an upward movement of the upper tube in the fuse-box for protecting articles within the building, substantially as and for the purposes stated.

ADOLPH A. HANSON.
